UNITED STATES PATENT OFFICE.

WILLIAM J. HALL, OF PAWTUCKET, RHODE ISLAND.

EVENER MECHANISM FOR COTTON-OPENERS OR THE LIKE.

SPECIFICATION forming part of Letters Patent No. 767,750, dated August 16, 1904.

Application filed November 1, 1901. Serial No. 80,725. (No model.)

To all whom it may concern:

Be it known that I, WILLIAM J. HALL, a subject of the King of Great Britain, residing at Pawtucket, in the county of Providence, State 5 of Rhode Island, have invented a certain new and useful Improvement in Evener Mechanisms for Cotton-Openers or the Like, of which the following is a specification, reference being had therein to the accompanying drawing.

10 The objects of the invention are to simplify and cheapen the construction of evener mechanism and to produce an improved mechanism having a convenient arrangement of the parts thereof which shall render the same 15 readily accessible for all necessary purposes and shall relieve all obstruction or concealment of the working parts of the machine.

An embodiment of the invention is represented in the accompanying drawing, which 20 latter shows in elevation the said embodiment combined with certain parts of a cotton-opener or the like machine.

Having reference to the drawing, 1 designates a portion of the framing at the feed end 25 of a cotton-opener or the like machine, 2 a feed-roll, and 3 3 3, &c., a series of feed-plates above said feed-roll and coöperating therewith.

4 4 4 designate a train of gearing of usual 30 or suitable character intervening between the feed-roll 2 and the shaft 51 of the upper cone 5 for the purpose of transmitting motion to the said feed-roll from the upper cone. The lower cone is designated 6, the cone-belt 7, 35 and the cone-belt shifter 8. A portion of the motion-transmitting train of gearing by which the lower cone is actuated is indicated at 81.

Instead of being located at the side or end 40 of the machine, alongside and beyond the machine proper, as ordinarily the case in practice, the cones 5 and 6 and cone-belt shifter 8 are arranged by me transversely of the machine and below the feed-roll 2. This reduces the amount of floor-space occupied by the 45 machine, places the cones and cone-belt shifter in a less exposed position, gives access to the end of the machine, and is otherwise convenient and advantageous.

In connection with the plates 3 3 3, &c., I 50 employ a scale-lever system at 9, the latter

being arranged wholly above the feed-plates. Said system is of the well-known character, and various forms and arrangements thereof are employed in the art. At 91 is indicated portion of a rod intervening in customary 55 manner between the inner mechanism and the main or weighted lever 10, pertaining to the said scale-lever system. Said lever is located above the other portions of the said system. 101 is the weight that is applied to the outwardly-extending arm of the said lever.

In further conformity with my invention I connect the cone-belt shifter 8 to a rack-bar 11, sliding in a direction crosswise of the machine and lengthwise of the cones 5 and 6. 65 The said cone-belt shifter and rack-bar are both located beneath the feeding devices. I combine the said rack-bar with the main or weighted lever 10 of the scale-lever system above the feed-rolls by means of operating 70 connections comprising, preferably, a spur-pinion 12, meshing with the teeth of said rack; a spur-gear 13, compounded—*i. e.*, fast—with said spur-pinion; a quadrant 14, meshing with the teeth of said spur-gear and pivoted at 75 141, and a rod 15, connecting said quadrant with said main or weighted lever 10 of the scale-lever system. The pivotal support 142 of the quadrant is located beyond the corresponding side framing of the machine, 80 and rod 15 is located outside of said side framing. For convenience of adjustment the rod 15 is furnished with a yoke 151 at its upper end fitting the lever 10, and said yoke is equipped with an adjusting or set screw 152, 85 making contact by its lower end with said lever. By turning said screw any desired adjustment of the cone-belt shifter relatively to the cones 5 6 may be effected.

I claim as my invention—

1. In evener mechanism for cotton-openers and the like machines, in combination, the feeding devices, the cones extending transversely across the machine below the said feeding devices, a cone-belt, the cone-belt 95 shifter and rack-bar located beneath the feeding devices and movable transversely of the machine, the scale-lever system located above the feeding devices and having the outwardly-extending main or weighted lever, the rod 100

connected with said lever and depending therefrom, and the quadrant operated through the said rod and in operative engagement with the said sliding rack-bar to move the rack-bar 5 and cone-belt shifter transversely across the machine, substantially as described.

2. In evener mechanism for cotton-openers and the like machines, in combination, the feeding devices, the cones extending transversely across the machine below the said feeding devices, the cone-belt, the cone-belt shifter located beneath the feeding devices and movable transversely of the machine, the scale-lever system located above the feeding devices 10 and having the outwardly-extending main or weighted lever, the rod connected with said lever and depending therefrom at the side of the machine, and direction-changing transmitting connections by means of which the 15 vertical movement of the rod is converted directly into a movement of the cone-belt shifter transversely across the machine, substantially as described.

3. In evener mechanism for cotton-openers and the like machines, in combination, the 25 feeding devices, the cones extending transversely across the machine below the said feeding devices, the cone-belt, the cone-belt shifter and rack-bar located beneath the feeding devices and movable transversely of the machine, the scale-lever system located above the feeding devices 30 and having the outwardly-extending main or weighted lever, the rod connected with said lever and depending therefrom, the quadrant operated through the said rod, and the compound gear and pinion 12, 13, in operative engagement with the quadrant and rack-bar, respectively, substantially as described.

In testimony whereof I affix my signature in 40 presence of two witnesses.

WILLIAM J. HALL.
